UNITED STATES PATENT OFFICE.

SILAS WARREN WRIGHT, OF CANTON, NEW YORK.

DESIGN FOR A SLEIGH-KNEE.

SPECIFICATION forming part of Design No. 34,574, dated May 28, 1901.

Application filed April 25, 1901. Serial No. 57,511. Term of patent 14 years.

To all whom it may concern:

Be it known that I, SILAS WARREN WRIGHT, a citizen of the United States, residing at Canton, in the county of St. Lawrence and State 5 of New York, have invented and produced a new and original Design for a Sleigh-Knee, of which the following is a specification, reference being had to the accompanying drawings, forming a part thereof.

Figure 1 is a perspective view. Fig. 2 is a vertical section. Fig. 3 is a top plan view.

As shown in the drawings, the leading or material feature of my design consists of an inclined main stem, out of the top of which 15 arise two branches, of unequal length, curving in opposite directions and terminating in a horizontal plane, and out of the bottom of which main stem spring two branches, of substantially equal length, also curving in opposite directions and terminating in a horizontal plane which is parallel with the plane in which the upper branches terminate, the ver-

tical planes in which these respective branches lie being at a right angle to each other.

A is the inclined main stem. 25

a is the longer of the upper branches, and a' the shorter.

b and b' are the lower branches, substantially of equal length.

C is an enlargement centrally disposed upon 30 the inclined main stem, out of which the respective branches spring.

d represents screw-holes in the several branches.

Having described my invention, what I 35 claim as new, and desire to secure by Letters Patent of the United States, is—

The design for a sleigh-knee, as herein shown and described.

SILAS WARREN WRIGHT.
